UNITED STATES PATENT OFFICE.

WILLIAM S. THOMSON, OF PLANTSVILLE, CONNECTICUT, ASSIGNOR TO THE H. D. SMITH & COMPANY, OF PLANTSVILLE, CONNECTICUT, A CORPORATION.

GRINDING AND POLISHING MACHINE.

1,257,548.

Specification of Letters Patent. Patented Feb. 26, 1918.

Application filed April 26, 1917. Serial No. 164,601.

To all whom it may concern:

Be it known that I, WILLIAM STRATTON THOMSON, a citizen of the United States, residing at Plantsville, in the county of 5 Hartford and State of Connecticut, have invented certain new and useful Improvements in Grinding and Polishing Machines, of which the following is a specification.

My invention relates to improvements in 10 grinding and polishing machines, and the object of my improvement is simplicity and economy in construction and convenience and efficiency in use, and involves certain improvements on the machine shown and 15 described in my Patent No. 1,137,033, April 27, 1915.

In the accompanying drawing:

Figure 1 is a front elevation of a grinding and polishing machine embodying my 20 invention.

Fig. 2 is a side elevation of the upper part.

Fig. 3 is a sectional view, on an enlarged scale, on the line *x-x* of Fig. 2, one of the 25 bearing heads being shown in side elevation.

Fig. 4 is a sectional view on the line *y-y* of Fig. 3.

Fig. 5 is a sectional view, corresponding to Fig. 3, of a modified form of structure.

30 My improved grinding and polishing machine comprises a casing 10 in which is operatively housed a shaft 11 which projects outwardly therefrom and on the outer end of which is mounted a grinding or polishing 35 wheel 12, and the operation of which is controlled by a handle 13. The casing 10 is a shell-like structure and comprises a body portion composed of the pedestal portion 14 having tapered front and rear walls and 40 merging into the base 15 at the lower end and at the upper end merging into the box-like head 16, and the upper end is closed by a cover 17 which may be secured by bolts 18. The shaft 11 is mounted in ball 45 bearings 19 provided in a pair of journal heads 20 positioned in the casing head 16. The driven pulley 21 is shrunk on the shaft 11 between the journal heads 20 and the belt 22 rests on the upper face thereof and drops 50 downwardly to the driving pulley on a counter shaft directly below the same. The shaft 11 projects through a vertical slot 23 in the end wall of the casing head 16 and

is provided with means for being raised and lowered to be described.

Below the pulley 21 the casing 10 is provided with a bridge 24, cast integral therewith and comprising cross-members 25, one on each side of the pulley 21, and a plate-like member 26 at the middle and supported by the said cross-members 25. The said plate-like member 26 is just below the pulley 21 and serves as a brake plate and may be provided with a cushioning member in the form of a piece of leather 27 for engaging directly with the pulley and braking the same when the pulley is lowered thereon.

The shaft 11 as stated is operatively supported by bearings 19 provided in the journal heads 20. The journal heads 20 comprise a head proper 28 provided with an axial bore 29 in which is positioned the shaft 11 and vertical ways 30 at the front and rear, suitable to slidably engage with guide ways 31 secured to the casing head 16 by 55 screws 32 and 33, and having a neck or stem 34 extending downwardly from the said head proper 28. The neck 34 of each of the bearing heads 20 fits into a hole 35 provided in the upwardly directed branch 36 or a 60 generally U-shaped cross-member 37, and is held in place by a set screw 38.

The body portion or middle portion 39 of the cross-member 37 extends across below the bridge 24 between the two journal 65 heads 20.

The cross-member 37 is adjustably supported adjacent each end of the body portion 39 by means of a stud 40 which connects with a yoke 41. The yokes 41 are supported 90 from an auxiliary shaft 42, and the said shaft 42 is supported eccentrically in the end disks 43, rotatively housed in bosses 44 in the side walls of the casing.

The studs 40 have left handed threads on 95 one end and right hand threads on the other end, the upper end being screwed into a threaded hole 45 in the cross-member 37 and the lower end is secured in the threaded hole 46 in the upper end of the yoke 41. 100 The yoke 41 is provided in the lower portion with a slot 47 which extends transversely relatively to the vertical axial plane of the shaft 11 and supporting stud 40, and which is a fit for and in which is operatively positioned the auxiliary shaft or rod 105

42. The two yokes 41 are in horizontal alinement and the auxiliary shaft 42 extends therethrough, the end portions thereof being secured in the disks 43.

5 As the disks or eccentrics 43 are rotated the auxiliary shaft 42 is moved therewith in an arc and the same is accordingly raised and lowered as well as swung back and forth relatively to the vertical axial plane. The 10 slot 47 permits of the cross-wise movement of the auxiliary shaft 42 while the yoke 41, stud 40, and journal head 20 are maintained constantly in the same axial and vertical plane, and the ways 30 and 31 permit of 15 vertical movement of these parts responsive to raising and lowering of the auxiliary shaft 42.

The auxiliary shaft 42 extends outwardly through the disk 43 at one side and has the 20 handle 13 mounted thereon, and a stop pin 48 is provided on the casing 10 for limiting the movement of the handle 13 in one direction, the movements of the handle 13 back and forth serving to raise and lower the 25 shaft 11.

The ways 31 comprise strips of material of uniform cross-section and suitable length positioned in the casing head 16 and adjacent and parallel with the front and back 30 walls 61 thereof. These have a V formation on the inner face 62 and are flat along the outer face 63, and have a screw threaded hole 64 at about the middle of the rear face 63 suitable for receiving the supporting 35 screw 32. These screws 32 pass through holes 67 in the outer wall 61 and the heads 65 engage with the counter faces of the said outer wall 61, preferably in a counter bored seat 66 provided therefor.

40 The screws 33 are headless and are engaged with screw threaded holes 68 in the walls 61 and engage with their inner ends against the outer face 63 of the track or way 31, and serve as backing screws in opposition to the middle supporting screws 32, there being two of the backing screws 33, one above and one below the supporting screw 32 in each case.

45 As described, the tracks or ways 31 are substantially parallel with the walls 61 and they are in spaced relation thereto, being spaced therefrom by a small space 69 sufficient with the limited freedom of movement permitted by the screw supporting means 55 provided to permit of a slight adjustment of the said tracks to provide for properly guiding the journal heads 20 in their movement substantially in a vertical plane.

The journal or bearing head 20 has an 60 axial bore 50 at the middle portion that receives a reduced portion 51 of the shaft 11, and the end portions 52 are enlarged suitably to receive the parts that compose the ball bearings proper, composed of the inner 65 cones 53, and outer cones 54, and the balls

55. Thus the bearing structure of the journal heads 20 is in each case duplex, having two bearings proper, in spaced relation, there being accordingly a total of four bearings proper engaged with the shaft.

Because of the duplex structure of the two trunnion heads I find the use of the cross-member 37 of particular advantage when it is necessary to adjust the bearings, in that the same serves to unite the two journal heads 20 together structurally as a unit and any such adjustment does not affect the alinement of the bearings.

70 That is to say, turning one of the studs 40 one way or the other to raise or lower 80 one end of the shaft has no effect whatsoever on the relative alinement of the shaft and the bearings, such as would be the case were no such cross-member provided.

Also, the structure described serves to relieve the tracks and the supporting screws therefor of side strain in the engagement with the journal heads.

85 In the modified form of structure the journal heads 20^a and the cross-members 90 37^a are all parts of a unitary carriage structure 56 of U-shape generally, the other structural features being substantially as have already been described.

95 I claim as my invention:—

1. In a grinding and polishing machine, a casing having a casing head at the upper end, a pair of journal heads slidably mounted in the said casing head and having bearings for a shaft, a cross-member rigidly 100 connecting the said journal heads, and hand operated means for raising and lowering the said cross-member and journal heads as a unit.

105 2. In a grinding and polishing machine, a casing, a shaft for a grinding wheel housed in the said casing and supporting a driving pulley, a pair of journal heads, one on each side of the said pulley, bearings in the said heads engaged with the said shaft, a bridge-brake positioned below the said pulley, a cross-member rigidly inter-connecting the said journal heads and extending across between the said heads below the said bridge-brake and hand operated means for raising 110 and lowering the said cross-member and heads.

115 3. In a grinding and polishing machine, a casing, a shaft for a grinding wheel housed in the said casing and supporting a driving pulley, a pair of journal heads, one on each side of the said pulley, bearings on the said heads engaged with the said shaft, a bridge-brake positioned below the said pulley, a cross-member rigidly inter-connecting the 120 said journal heads and extending across between the said heads below the said bridge-brake, hand operated means for raising and lowering the said cross-member and heads, and adjustable means serving to connect the 125 130

said cross-member with the said hand operated means.

4. In a grinding and polishing machine, a pair of bearing structures for supporting a shaft, and positioned in spaced relation suitably to receive the driving pulley therebetween, a bridge-brake positioned between the said bearing structures, below the pulley receiving space, shifting means for shifting the said bearing structures so as to move the pulley toward and away from the said

bridge-brake, connecting means for connecting the said bearing structures and shifting means and operative to permit of adjustment, and a cross-member for interconnecting the said bearing structures serving to maintain the alignment thereof independently of the said connecting means. 15

WILLIAM S. THOMSON.
